United States Patent Office

AUGUSTUS J. WARNER, OF BROOKLYN, NEW YORK, ASSIGNOR TO HIMSELF AND JAMES E. CONOR.

Letters Patent No. 61,779, dated February 5, 1867.

IMPROVED WINDOW-BLIND FASTENING.

The Schedule referred to in these Letters Patent and making part of the same.

TO ALL WHOM IT MAY CONCERN:

Be it known that I, AUGUSTUS J. WARNER, of the city of Brooklyn, in the State of New York, have invented a certain new and useful improvement in Window-Blind Fasteners or Shutter Holders; and I do hereby declare that the following is a full, clear, and exact description of the construction and operation of the same, reference being had to the accompanying drawings, and to the letters and marks thereon.

My improvement is intended to be used in fastening or holding back the usual blind or shutter when it is fully opened and against the wall or side of the building; the plate to which the arm or lever of the fastener is connected being screwed or otherwise suitably affixed to the casing or frame of the window, and the arm or lever, when the shutter is opened or back, pressing against the inner edge of the blind or shutter. The drawings, forming part of this specification, represent my invention—

Figure 1 thereof being a view with the arm or lever *a* placed in three different positions in relation to the plate *b*, the one position, indicated by black lines, being that of the arm or lever when it is in a perpendicular line with the wall, the shutter not being opened; the second position, indicated by red lines, being that when the lever or arm is elevated and prepared to be turned down; and the third position, that of the arm, indicated in blue lines, when holding the shutter opened, the last position being at right angles to the first.

Figure 2 shows the arm *a* when in the perpendicular position.

Figure 3, the arm without the plate *b*; and

Figure 4, by a sectional view, the plate *b*.

In each of these figures like parts are indicated by the same marks and letters.

The plate *b* has holes for the screws, and ears or lugs *c* for sustaining the pin or pivot *d*, on which the lever moves. The lever or arm *a* has a projection, *e*; which, when the shutter is open, and the lever is turned to hold the shutter, rests against the projecting end *f* of the recess *g* of the plate. The larger end of the arm or lever has a slot, *h*, in which plays the pin or pivot *d*; and the smaller end is curved, the one side of the curved part having a face, *i*, which comes against the shutter when it is held open. The movements of the arm or lever from the one position to the other can be easily and conveniently made. When not in use to hold the blind or shutter open, the lever will be folded against the casing-plate or strip out of the way; and when operating to hold the shutter open it will occupy but little space, and be readily reached and handled. As is evident, the parts of this holder or fastener can be made by casting or by swaging, and of any of the metals commonly used for like articles.

What I claim as my invention, and desire to secure by Letters Patent, is—

A shutter or blind-holder or fastener, having the slot *h* and face *i* constructed and operated substantially as herein described.

This specification signed this 25th day of September, 1866.

AUG. J. WARNER.
